200,563

INSTRUMENT FOR STIMULATING AND AROUSING HEARTBEAT

Robert P. Brooks, 511 E. North St., Warrensburg, Mo.

Filed Sept. 9, 1964, Ser. No. 81,655

Term of patent 14 years

(Cl. D83—1)

Fig. 2.

Fig. 3.

Fig. 4.

FIG. 1 is a perspective view of an instrument for stimulating and arousing heartbeat, showing my new design;

FIG. 2 is a top plan view thereof;

FIG. 3 is an elevational view thereof showing the side opposite to that shown in FIG. 1; and

FIG. 4 is a bottom plan view thereof.

This is a continuation in part of application Serial No. D.71,830 filed Sept. 24, 1962.

I claim:

The ornamental design for an instrument for stimulating and arousing heartbeat, as shown and described.
